(57) **CLAIM**

The ornamental design for conjoining device, as shown and described.

DESCRIPTION

FIG. 1 is a perspective, exploded view illustrating my design for a conjoining device;

FIG. 2 is a front, exploded elevation view thereof;

FIG. 3 is a side, exploded elevation view thereof;

FIG. 4 is a perspective view thereof,

FIG. 5 is a front elevation view thereof,

FIG. 6 is a side elevation view thereof,

FIG. 7 is a top view thereof; and,

FIG. 8 is a bottom view thereof.
